EXPANDED PLASTIC SHEET MATERIAL

James F. Emerick, Struthers-Coitville Road,
Lowellville, Ohio

Filed Aug. 26, 1964, Ser. No. 81,443

Term of patent 14 years

(Cl. D87—3)

FIGURE 1 is a top plan view of an expanded plastic sheet material, showing my new design;

FIGURE 2 is a cross sectional view of the expanded plastic sheet material shown in FIGURE 1, taken on line 2—2 of FIGURE 1;

FIGURE 3 is a top plan view of a second embodiment of the design shown in FIGURE 1;

FIGURE 4 is a cross sectional view thereof taken on line 4—4 of FIGURE 3;

FIGURE 5 is a vertical section on line 5—5 of FIGURE 1; and FIGURE 6 is a vertical section on line 6—6 of FIGURE 3.

I claim:

The ornamental design for an expanded plastic sheet material, as shown and described.
